(57) **CLAIM**

The ornamental design for cutting tool for die cut, as shown and described.

DESCRIPTION

1. Cutting tool for die cut

1.1 : Front

1.2 : Top

1.3 : Bottom

1.4 : Right

1.5 : Cross-sectional view taken along the section line

1.5-1.5 of Fig. 1.2

1.6 : Cross-sectional view taken along the section line

1.6-1.6 of Fig. 1.2

1.7 : Cross-sectional view taken along the section line

1.7-1.7 of Fig. 1.2

1.8 : Enlarged view of the portion 1.8 of Fig. 1.3.

The portions shown in broken lines do not form part of the design; the dotted-dashed line shows only the boundary between the part for which design registration is sought as a partial design and the other part; back and left views are omitted because they are mirror image of front and right views.
